(57) **CLAIM**

The ornamental design for an elliptical dog bed, as shown and described.

DESCRIPTION

FIG. 1 is a front elevation view of an elliptical dog bed showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof; and,

FIG. 7 is a perspective view thereof.

The broken lines in the figures illustrate portions of the elliptical dog bed that form no part of the claimed design.

1 Claim, 7 Drawing Sheets
